DESIGN FOR A WATCH BRACELET STRAP

Saul Ritter, New York, N. Y.

Application November 19, 1936, Serial No. 66,017

Term of patent 3½ years

To all whom it may concern:

Be it known that I, Saul Ritter, a citizen of the United States, residing in New York city, in the county of New York and State of New York, have invented a new, original, and ornamental Design for a Watch Bracelet Strap as shown, of which the following is a specification, reference being had to the accompanying drawing, forming part thereof.

I claim:

The ornamental design for a watch bracelet strap, as shown.

SAUL RITTER.
